UNITED STATES PATENT OFFICE

ALBERT DE LA MARE, OF SAN FRANCISCO, CALIFORNIA

DESIGN FOR A FIRE TRUCK

Application filed July 23, 1930. Serial No. 36,442. Term of patent 7 years.

To all whom it may concern:

Be it known that I, ALBERT DE LA MARE, a citizen of the United States of America, residing at San Francisco, in the county of San Francisco and State of California, have invented a new, original, and ornamental Design for a Fire Truck, of which the following is a specification, reference being had to the accompanying drawing, forming a part thereof.

I claim—

The ornamental design for a fire truck as shown.

ALBERT DE LA MARE.
